DOUBLE HUNG WINDOW SASH CONSTRUCTION

Gordon A. Gray, Deerwood, Minn.

Application June 10, 1955, Serial No. 514,418

2 Claims. (Cl. 20—52.2)

My invention relates to window constructions; and in particular, it relates to a weather stripping and sash control combination for mounting a pair of sashes in a window frame.

An object of my invention is to provide a window construction comprising weather stripping and sash control which is more simple than any now known in the art.

Another object of my invention is to provide an improved and simple window construction comprising a frame of simple construction wherein the side jambs thereof have flat unbroken forwardly facing surfaces between the stops, having eliminated parting strips and grooving of the side jambs, and a weather stripping and sash control combination for mounting sashes in the frame which comprise only two pieces easily installed on each side of the frame.

Another object of my invention is to provide a novel and improved window construction which eliminates parting strips, sash balances, dust pads, intricate grooving of the side rails of the sashes, and cutting back of the check rails of the sashes to fit around the parting strip, and wherein the sashes may be lifted out of the frame without removing any of the stops.

Another object of my invention is to provide a novel and improved window construction comprising a weather stripping and sash control combination of two pieces on each side of the frame which are connected by screws to the frame for limited movements toward and away from the side jambs thereof; wherein, by tightening or loosening the screws the pressure on the sashes of the window will be kept even, and as weather conditions change the tightening or loosening of the screws allows for swelling or shrinking, respectively.

Further objects and advantages of my novel and improved weather stripping and sash control combination are that it may be used on any standard check rail window with no special frame needed; it is absolutely noiseless; it is air tight with three air chambers furnishing ample insulation; and it needs no paint nor the sash edges which come in contact with it.

These and other objects and advantages of my invention will become apparent in the course of the following specification and claims, reference being had to the accompanying drawings wherein:

Fig. 1 is a view in front elevation of the double sash window construction of my invention;

Fig. 2 is an enlarged view in horizontal section taken on the line 2—2 of Fig. 1;

Fig. 3 is an enlarged view partly in vertical section and partly in end elevation as viewed on line 3—3 of Fig. 1;

Fig. 4 is an enlarged detailed view of a portion of Fig. 2; and

Fig. 5 is a view similar to Fig. 4 showing different positions of some of the parts thereof in removing or inserting the inner sash.

Referring more particularly to the drawings, wherein like parts will be indicated by the same numerals, the numeral 10 indicates in its entirety a window frame com-

2

prising a pair of spaced, parallel, longitudinally-extending, oppositely-disposed vertical side jambs 11. Vertically disposed blind stops 12 and inner stops 13 are assembled with side jambs 11 to define the oppositely-disposed, inwardly opening, longitudinally-extending vertical sash ways 14. Referring in particular to Figs. 4 and 5, each side jamb 11 defines a flat, generally unbroken, inwardly facing surface 15 between the blind stop 12 and inner stop 13 assembled therewith. The construction of frame 10 is extremely simple as I have eliminated parting strips and grooving of the side jambs 11 between the stops 12 and 13.

I provide a novel and improved weather stripping and sash control combination comprising only two pieces on each side of the frame 10. One piece is a longitudinally-extending, integral guide member 16 which defines a pair of laterally-spaced, parallel, longitudinally-extending ribs 17; a plate-like longitudinally-extending central portion 18 which extends laterally between and connects the ribs 17; a pair of laterally-spaced longitudinally-extending plate-like side portions 19, one of which extends from one of the ribs 17 to the lateral edge 20 of guide member 16 and the other extends from the other rib 17 to the lateral edge 21 of guide member 16; and a pair of laterally-spaced parallel flanges 22 which are disposed at right angles to side portions 19 and project therefrom one at lateral edge 20 and the other at lateral edge 21. The other piece is a longitudinally-extending, yieldable, resilient pressure member 23 of generally U-shaped cross section which comprises a generally plate-like intermediate portion 24 and a pair of laterally-spaced leg portions 25 which extend obliquely in generally the same direction from opposite side edges of intermediate portion 24 in diverging relationship. Intermediate portion 24 is slightly bowed in a direction towards the free ends 26 of leg portions 25; and each of the leg portions 25 is bent outwardly generally at right angles at its free end 26 to define a foot portion.

One guide member 16 and one pressure member 23 are connected to each of the side jambs 11 for limited movements toward and away from the side jambs 11. One pressure member 23 is disposed between one side jamb 11 and its associated guide member 16, and the other pressure member 23 is disposed between the other side jamb 11 and its associated guide member 16. Preferably, each guide member 16 has a plurality of vertically spaced, aligned apertures 27 formed in the central portion thereof; and similarly, each pressure member 23 has a plurality of vertically spaced, aligned apertures 28 formed in its intermediate portion 24. Adjacent apertures 28 are vertically spaced a distance equal to the distance between adjacent apertures 27 so that each of the apertures 27 may be horizontally aligned with one of the apertures 28. Preferably, I provide a plurality of generally horizontally disposed wood screws 29 for fastening guide members 16 and pressure members 23 to their respective side jambs 11. Each screw 29 extends through one of the apertures 27 and the adjacent horizontally aligned aperture 28 and is screwed into the side jamb 11 associated with the guide member 16 and pressure member 23 through which it extends. Screws 29 are screwed into side jambs 11 a distance substantially less than the length of the screw to permit the relative movements of guide members 16 and pressure members 23 toward and away from their associated jambs 11.

In considering more specifically the mounting of guide members 16 and pressure members 23 reference may be particularly made to Figs. 4 and 5. It is noted that guide members 16 are mounted in sash ways 14 each in inwardly spaced generally parallel relationship with its associated side jamb 11 with ribs 17 thereof projecting inwardly or away from jambs 11. Flanges 22 are dis-

posed adjacent stops 12 and 13 but with clearance therebetween to permit the movement of guide members 16 in the sash ways 14, and flanges 22 are generally parallel to the sides of sash ways 14 defined by stops 12 and 13. It is noted that the intermediate portions 24 of pressure members 23 engage each of the guide members 16 along laterally spaced longitudinally-extending edges indicated by the numeral 30 adjacent the ends of intermediate portions 24, and the free ends 26 of diverging leg portions 25 engage side jambs 11 to define three insulating air chambers 31, 32 and 33 at each side of the frame 10 which provide ample insulation. It is clear that pressure members 23 might be reversed in positions so that intermediate portions 24 thereof engage the side jambs 11 and the free ends 26 thereof engage the guide members 16. Guide members 16 and pressure members 23 are relatively movable with respect to the wood screws 29 extending therethrough toward and away from their associated side jambs 11 with the movements of each guide member 16 away from its associated side jamb 11 being limited by the heads 34 of screws 29. The screws 29 extending through one guide member 16 and its adjoining pressure member 23 are vertically aligned and disposed in common vertical planes with the vertically aligned screws 29 extending through the other guide member 16 and its adjoining pressure member 23. Screws 29 are disposed generally centrally between blind stops 12 and inner stops 13.

I provide a pair of sashes 35 having longitudinally-extending, outwardly-opening grooves 36 formed one in each of their vertically disposed side rails 37. The grooves 36 in the same sash 35 are oppositely disposed. Sashes 35 are mounted between guide members 16 on opposite sides of the common vertical planes of screws 29, see Fig. 2, with ribs 17 fitting into the grooves 36, oppositely disposed ribs 17 fitting into the grooves 36 of the same sash 35, for mounting sashes 35 for vertically upward and downward movements. Pressure members 23 urge guide members 16 into engagement with side rails 37 of sashes 35 so that sashes 35 may be vertically positioned within frame 10 in any desired position; and this eliminates the use of sash balances. By tightening or loosening screws 29, the limit of inward movements of guide members 16 may be adjusted toward or away from their associated jambs 11 to allow for swelling or shrinking so that the pressure on sashes 35 may be kept even in spite of swelling or shrinking caused by changes in weather conditions. Thus, sashes 35 will never be loose or rattle in the frame 10, or will never be tight in the frame 10 so that vertical movements thereof are difficult.

My invention provides for completely removing sashes 35 without taking off any of the stops 12 and 13. Both of the sashes 35 should be first moved to their lowermost positions. Then, referring in particular to Figs. 2 and 5, the sash nearer the operator is moved toward one of the jambs 11, either to the right or left, and the opposite side of the same sash 35 is moved toward the operator. If the inner one of the sashes 35 is removed first, the outer sash 35 may then be removed in the same manner, if desired. The movement of either of the guide members 16 toward its associated side jamb 11 against the bias of its adjoining yieldable pressure member 23 provides for both ease and simplicity in removing and inserting the sashes 35; and yet, guide members 16 and pressure members 23 remain connected to the side jambs 11 though the sashes 35 have been removed, and may not be replaced in position each time the sashes are removed and then inserted in the frame 10.

It will be obvious to those skilled in the art that my invention may be modified by many substitutions and equivalents, and that this disclosure is intended to be illustrative only; therefore, I intend to be limited solely by the scope of the appended claims.

What I claim is:

1. A weather stripping and sash control combination comprising a longitudinally extending integral guide member formed of metallic sheet stock consisting of a generally planar longitudinally extending central portion, a pair of laterally spaced parallel longitudinally extending generally U-shaped rib portions coextensive with and interconnected by said central portion and projecting outwardly from the plane of said central portion each in the same direction, a pair of laterally spaced longitudinally extending generally planar side portions coextensive with and disposed in coplanar relationship with said central portion and each extending from a different one of said ribs to a different one of the lateral edges of said guide member, and a pair of laterally spaced parallel longitudinally extended flanges disposed generally normal to said side portions and projecting therefrom each at a different one of the lateral edges of said guide member in a direction opposite to the direction of projection of said rib portions; said guide member being adapted to be vertically disposed generally parallel to one side jamb of a window frame between vertically disposed laterally spaced stops associated with the same side jamb with the rib portions of said guide member projecting away from said side jamb, said guide member being adapted to be connected to said side jamb for limited movements toward and away from said side jamb; and a longitudinally extended yieldable resilient pressure member which is generally coextensive with said guide member and of generally U-shaped cross section comprising a generally plate-like intermediate portion and a pair of laterally spaced diverging leg portions extending obliquely outwardly from opposite side edges of said intermediate portion; said pressure member being adapted to be disposed between and engaging said side jamb and said guide member to yieldably urge said guide member to its limit of movement away from said side jamb.
2. In a double hung window sash structure, a window frame comprising a pair of spaced parallel longitudinally extending oppositely disposed vertical side jambs and vertically disposed inner stops and blind stops, an inner stop and a blind stop in laterally spaced relationship assembled with each side jamb to define a pair of oppositely-disposed inwardly-opening longitudinally-extending vertical sash ways, each side jamb defining a flat generally unbroken inwardly-facing surface between the stops assembled therewith; two longitudinally extended guide members, each guide member being integral and formed of metallic sheet stock and consisting of a generally planar longitudinally extending central portion, a pair of laterally spaced parallel longitudinally extending generally U-shaped rib portions coextensive with and interconnected by said central portion and projecting outwardly from the plane of said central portion each in the same direction, a pair of laterally spaced longitudinally extending generally planar side portions coextensive with and disposed in coplanar relationship with said central portion and each extending from a different one of said ribs to a different one of the lateral edges of said guide member, and a pair of laterally spaced parallel longitudinally extended flanges disposed generally normal to said side portions and projecting therefrom each at a different one of the lateral edges of said guide member in a direction opposite to the direction of projection of said rib portions; each of said guide members being mounted in a different one of said sash ways in inwardly spaced generally parallel relationship with the side jamb thereof with the rib portions of each guide member projecting inwardly away from said side jamb; a pair of longitudinally extended yieldable resilient pressure members each associated and coextensive with a different one of said guide members; each of said pressure members being of generally U-shaped cross section and comprising a generally plate-like intermediate portion and a pair

of laterally spaced diverging leg portions extending obliquely outwardly from opposite side edges of said intermediate portion; each of said pressure members being disposed between and engaging a different one of said side jambs and its associated guide member; means connecting each of said guide members to its associated side jamb for limited movement toward and away from its associated side jamb and whereby each pressure member yieldably urges a different one of said guide members to its limit of movement away from its associated side jamb; and a pair of sashes having side rails each sash having a pair of longitudinally extending outwardly opening grooves formed therein with one groove being formed in each of the vertically disposed side rails of

each sash; said sashes being mounted between said guide members with the ribs thereof fitting into the grooves of said sashes with the coplanar central portion and side portions of each guide member disposed adjacent and engageable with the vertical side rails of said sashes for mounting said sashes for controlled vertically upward and downward movements.
